UNITED STATES PATENT OFFICE

2,489,014

BRUSH CUTTER

Norbert V. Degelman, Darlingford, Manitoba,
Canada

Application January 25, 1946, Serial No. 643,385

1 Claim. (CL 56—25)

1

My invention relates to improvements in brush cutters, an object of the invention being to provide a device of the character herewithin described by the use of which roadside brush, or railroadside brush may be quickly and economically cut down to any desired height, and either with the top plane thereof horizontal, or at a desired angle of inclination.

A further object of my invention is to provide a device of the character herewithin described which is primarily intended to be tractor-drawn, and is conspicuous for its simplicity and consequent low cost whereby its use may be widely adopted, and by unskilled persons, without the need of frequent servicing or the like.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings, in which—

Figure 1 is a plan view of my brush cutter.

Figure 2 is a view as seen from the line 2—2 of Figure 1.

Figure 3 is a fragmentary view of my brush cutter as seen from the line 3—3 of Figure 2.

In the drawings like characters of reference indicate corresponding parts in the different figures.

My invention comprises a substantially rectangular framework collectively designated 1 including as a part thereof a pair of converging members 2, to the bracket 3 connected to which a draw-bar is intended to be hitched.

Secured to my aforesaid framework is a pair of vertically disposed plates 4' of which one edge 5 is curved as seen in Figure 2. The plate 4' is provided with the obliquely disposed slot 6 in which is movable a tightener pulley assembly 7.

Mounted in bearings 8 and 9 is a power take-off shaft 10 to the inner end of which is connected a drive pulley 11 around which passes a belt 12. This belt passes around the tightener pulley 7 and also around the crank pulley 13 mounted upon a transversely extending cutter-bar assembly 14.

The cutter-bar assembly 14 comprises an elongated channel 15 from the end of which projects a cutter-bar support 16 and by cutter-bar per se 17. The channel 15 is suspended at the left end thereof (with respect to Figure 2) by means of the block 18 having trunnions 19 in the ends thereof whereby the block is rotatably held via

2

said trunnions in the flanges 19' of channel 15. Through the aforesaid block extends a screw-threaded aperture in which the screw-threaded rod 20 is mounted.

5 The extreme upper end of the rod 20 is cranked to provide a handle 21, and just below the handle passes through a plain aperture in a trunnion-supported block 22 at the upper end of my framework. In this case the trunnions 23 projecting 10 from the block support the projecting tangle-pieces 24 and since a pair of collars on the rod 20 at either side of the block 22 prevent end-wise movement of the rod it will be obvious that upon rotation thereof clockwise or counter-clockwise the left end of the channel 15 will move upwardly or downwardly.

The right-hand end of the channel 15 (with respect to Figure 2) is supported in a substantially similar manner to that which I have already described except that in this instance a block 25 is supported on trunnions 26 freely positioned in a pair of bearing portions 27 secured to and projecting upwardly above the flanges 19. The block 25 also provides an end-bearing to the screw-threaded rod 28 which is also cranked at the upper end thereof to provide a handle 29, rod 28 being however screw-threaded right up to the shoulder 30 of the handle and passing through an internally screw-threaded aperture 31 in a block 31 rotating via trunnions 32 in a pair of angle-pieces 33.

Thus, in the case of rod 28, as the same is rotated clockwise or counter-clockwise, the same will end shift upwardly or downwardly and carry with it the channel 15. To provide ways for the projecting portions of trunnions 26, it will be seen from Figure 2 that plate 4' is vertically slotted as at 34, as is also plate 4.

The supporting plate 16 is coterminous with the 40 right-hand end of the web portion 35 of channel 15, and mounted for reciprocal movement against the upper surface of said web is my aforesaid cutter-bar 17, the same being held against the web by virtue of a pair of studs 36 which project 45 through slots 37 in the cutter-bar. Secured to the root of the cutter-bar is a bifurcated and up-standing bearing 38 to which is secured the connecting rod 39, the other end of said connecting rod being secured to the crank assembly 40 operated by the aforesaid pulley 13.

Secured for rotation to the horizontal members 41 of my framework by means of the bolt assemblies 42 are sector plate 43, the same being semi-circularly slotted as at 44 to receive the nutted bolt assemblies 45, the bolts whereof are

welded or otherwise secured to the members 41 and project therefrom to the said slot. Positioned between the assemblies 42 and the slots 44 are axles 46 designed to receive ground wheels, and upon adjustment of the plates 43 about the assemblies 42 in either direction, it will be obvious that my framework may be raised or lowered.

At the junction of the members 2, it will be noted that I have provided a front end supporting assembly 47 comprising a small ground wheel 48 and bearing 49 therefor. By substitution of a longer or shorter supporting shaft 50 the front end may be raised or lowered in conformity with the rear end via the aforesaid sector plates 43. Obviously however, other means for adjusting the height of the front end may be resorted to as desired for the purpose in view.

Since many modifications can be made in the invention herein described and since the accompanying drawings have been prepared only to illustrate the relative arrangement and interaction of parts and not with regard to accuracy of dimensions for manufacturing purposes which in view of this disclosure I consider to entail merely mechanical skill together with the skill of the mechanical draftsman, and since many apparently widely different embodiments of this invention may be made within the scope of the accompanying claim without departing from the spirit and scope of the same it is intended that all matter contained in the accompanying specification shall be interpreted as illustrative only and not in a limiting sense and I desire only such limitations placed thereon as justice dictates.

What I claim as my invention is:

A brush cutting implement comprising in combination a wheel mounted, tractor-drawn framework, a cutter assembly including a cutter-bar

projecting from one side of said framework, means for operating said cutter-bar, means for adjusting the angle of inclination of said bar with respect to the horizontal, and through a vertical plane normal to the implement's direction of travel and for raising and lowering the same within the range of its angular adjustment and within said plane consisting of a pair of substantially vertically disposed, screw-threaded and rotatable rods, said cutter assembly being supported from the lower ends of said rods by self-aligning bearings, said rods being also mounted in self-aligning bearings on either side of said framework, said means for operating said cutter-bar comprising a power take-off shaft having a pulley thereon, and, in combination therewith, a pulley on said cutter assembly, and an adjustable tightener pulley on said framework for maintaining a belt extending around said two first mentioned pulleys falt regardless of the position or angle of said cutter assembly.

NORBERT V. DEGELMAN.
